PROCESS OF AND APPARATUS FOR TREATING MINERALS.

Application filed July 20, 1925. Serial No. 44,896.

REISSUED

This invention pertains to the art of milling, disintegrating or crushing of mineral bodies to a state of fine division, a classification or separation of such milled mineral without the loss of the finest constituents, and also provides for the drying, dehydration and calcination, or both, of such minerals.

The principal object of this invention is to disclose a method of milling a mineral, drying or calcining such milled mineral, and then separating the milled product into desired grades of fineness without the loss of the exceedingly fine particles produced by the milling operation. This method or process of operation may be effected in relatively simple, inexpensive apparatus, also disclosed and claimed by me.

Many minerals and clays which it is desired to dry and mill, such as, for example, diatomaceous earth, kieselguhr or infusorial earth, or such earths combined with clay, contain high amounts of absorbed or combined water or both forms of moisture. In the case of diatomaceous earth, the raw or crude mineral contains as much as 65% absorbed moisture. It has been found that most porous minerals in lump form, or minerals originally found with a high moisture content, resist a drying operation, after a portion of the water has been removed, because of the fact that the outer surfaces of the material insulate the inner portions, and thereby prevent the rapid penetration of drying heat. It is, therefore, seen that if the drying operation is performed on minerals in a finely divided form, the drying heat may be applied to much greater benefit. The most effective drying operation, therefore, is that in which the mineral material is first ground to a suitable state of division and then exposed to a heated medium or gas so that each individual particle is surrounded by the heating or drying medium. The latter mode of operation has been used on certain particular products by blowing the powdered or granular product into a receptacle or chamber, a heated gas being generally used. There has been difficulty experienced, however, in the subsequent separation of the powdered material from the gas. The dust problems arising from this method necessitating the use

of electrical dust collectors, spraying systems and the like. 55

It is acknowledged that certain units of equipment similar to those comprising the apparatus herein disclosed have been disclosed by the prior art, for example, conical air separating chambers have been used for such purpose, but to the best of my knowledge, such units have never been connected, as shown by me, nor was it possible to heat, separate, and mill or disintegrate a mineral in a closed circuit, and eliminate the loss of 65 finely disintegrated constituents.

The present invention discloses a process of drying mineral materials in a finely divided form (containing moisture) in a current of heated gas or other fluid and 70 then separating the dried material from said gas in suitable air separating apparatus, the dust being recovered by bringing it in contact with the moist or wet material just entering the process on which the dust is absorbed and retained. In this manner a dust loss is not created and the use of expensive or elaborate dust collecting machinery is obviated, the form of apparatus which has been found to be adapted to the process being 75 comparatively simple and inexpensive. My process is particularly adapted to the milling, drying, and separating operations encountered in the treatment of diatomaceous earth, kieselguhr or infusorial earth, or the like. It has been used with entire success in the production of powdered grades of diatomaceous earth of such fineness that only 80 1-5% is left on a 150-mesh screen, while about 20-40% of the material is less than 85 0.001 mm. in size. Inasmuch as the dried, powdered diatomaceous earth in this state of division weighs but 8 to 10 lbs. per cu. ft. great difficulty had hitherto been encountered in separating the dust of such product, 90 from the gas or other fluid used in conveying or separating apparatus. 95

The accompanying drawings give a diagrammatic illustration of my process and one modification thereof and at the same 100 time disclose an apparatus which may be used in its operation. Fig. 1 shows a process in which a mineral material is disintegrated, dried, and separated into various grades of fineness. Fig. 2 shows a modification of the process in which a mineral mate- 105

rial is disintegrated, dried, calcined and separated into various grades of fineness.

In Fig. 1 the raw or crude mineral (containing moisture) is fed from a suitable bin 4 to a preliminary milling machine 5 which in this case may be spiked rolls. The partly crushed mineral may then be fed through a tourniquet, scroll, or other feeding device 6 into an enclosed milling or disintegrating apparatus 7 of any appropriate design, for example, a swing hammer mill, from which the milled material is discharged by suitable means such as pipe means 8 into a fan, blower, or disintegrator 9 adapted to the conditions. This blower or disintegrator discharges the milled material through pipe means 10 into an air separator or cyclone 1 which is equipped with an outlet means 2 through which all excess air or gas or other fluid may be discharged. The base of the cyclone or separator 1 into which the milled mineral settles, may be provided with a tourniquet, scroll, or other feeding device 12 which discharges from means 13 into suitable pipe or cylindrical means 14, of requisite length and which may be made of cast iron, refractory tile, etc. A furnace, heater, or other suitable source of heated air, gas, or other fluid, for example, waste heat from another operation (provided such gas is at a temperature above 212° F.), indicated at 15 discharges into means 14 and the moist, milled material from cyclone 1 is thereby surrounded in means 14 with a heated gas or drying medium. This mixture of milled material and gas is discharged into a blower or disintegrator 16 which in turn discharges through means 17 into a second cyclone air separator or other suitable device 2. The discharge 18 from this second cyclone leads back to the milling or disintegrating apparatus 7 and thereby forms a closed circuit.

The above process and apparatus pertain directly to my invention and the dried and milled mineral may then be discharged through suitable feeding device 19 from the bottom of cyclone 2 but inasmuch as it has been heated during the drying operation in its passage through means 14, blower 16, and means 17, it may be desirable to cool said material before bagging or otherwise preparing the material for shipment. The milled and dried mineral may be, therefore, discharged from the base of cyclone 2 through suitable feeding mechanism such as a tourniquet 19 into means 20 leading into pipe means 21, provided with an inlet for cold air as indicated at 22. The finely divided and dried mineral matter is then sucked into a fan or impeller 23 of suitable design, and discharged through means 24 into cyclone 3, from which the coarser material is discharged through a valve, or scroll, or tourniquet, etc, 29, into a suitable container or bin 30 from which it may be removed

through means 31 and sacked, bagged, or otherwise prepared for shipment. Air containing exceedingly fine particles or dust, may be discharged through means 26 into a suitable dust collecting system indicated at 27 such as, for example, a stocking dust collector made of tubular fabric open-end containers, through which the air is blown, the dust being left on the interior of said tubular membranes. Eventually the dust falls to the base 28 of said stocking dust collector and may be withdrawn therefrom periodically and also bagged or otherwise prepared for shipment as a distinct and exceedingly fine grade of material.

The temperatures of the gases discharged into the atmosphere from the separating chamber 1 must not be too high, else a certain amount of very finely disintegrated material is lost through this outlet. The temperature of the exhaust gases at which the most effective operation takes place varies with the percentage of moisture in the crude or raw material being treated, the temperature to which the material is heated, the percentage of moisture in the material entering that separating chamber which exhausts into the atmosphere, and the velocity of the gases. For example, in the manufacture of disintegrated or finely divided diatomaceous earth from natural diatomaceous earth, which originally contained 40% free moisture, it was found that if the disintegrated material entering the air separating chamber 1 contained less than about 20% moisture, the exhaust gases 11 would show a loss of dust, while when the moisture content was greater, say 25%, there was no dust loss. This was true under identical conditions; that is, the degree of milling and velocity of gases was kept constant. Temperature of the gases going through blower 16 were approximately 500° F. while the gases being returned to the primary disintegrator 7 were about 225° so that some drying action also took place in means 8, 9, and 10. Supplies of heated gas may be introduced at disintegrator 7 or to pipe means 8, in addition to the gases introduced by heater or other source 15, whenever the material being fed into the system at 4 contains very large quantities of moisture.

Referring to Fig. 1, it is seen that the exhaust 18 from chamber 2 contains dust which is absorbed or retained by the moist material disintegrated in the mill 7 and that there is no dust loss from exhaust 11 from chamber 1, by reason of the moisture present in the material at this stage.

Fig. 2 refers to a modification of my process in which the temperatures to which the materials are heated are relatively high, for example, temperatures about 1400° F. or 1800° F. or higher may be reached in the calcining zone. This modification also em-

braces a step in which the heated gases from the calcining zone are passed through the previous zones and the heat contained in such heated gases is used in drying the mineral before it reaches the calcining zone. In this modification also dust loss is prevented in much the same manner as described in Fig. 1. The calcination disclosed by the following modification may be made on the raw, 10 disintegrated mineral either with or without the addition of suitable salts or chemicals; for example, it has been found that calcination of finely divided diatomaceous earth in the presence of salts of alkali metals produces a white, fluffy, and very desirable product.

In Fig. 2 the raw mineral is fed from a bin 55 or other suitable source of supply, to a suitable crushing machine 56, for example, 20 spiked rolls. The partly disintegrated mineral is then fed by a suitable mechanism 57 (which may be a scroll or belt conveyor), to an enclosed disintegrating apparatus 58 which may be a swing hammer mill or the like. The disintegrated mineral is then passed by suitable pipe means 59 through a fan or impeller 60 (which may be so designed as to give a certain amount of disintegrating action), through pipe means 61 to 25 a suitable air separating chamber 51. The exhaust 51' from said air separating chamber discharges into the atmosphere while the disintegrated material discharges from the air separating chamber 51 through a tourniquet, scroll, or other suitable means 62 into and through pipe means 63 into pipe means 64, which lead to a fan or impeller 65. The last mentioned fan discharges through pipe means 66 into a secondary air separating 30 chamber 52. The gas containing fine particles of matter is discharged from the air separating chamber 52 through pipe means 67 and lead back to the closed chamber containing the disintegrator 57.

The disintegrated material from air separating chamber 52 is discharged through a suitable feeding mechanism 68 which may be a tourniquet, scroll, or the like, into pipe means 69, which discharge directly into a 45 suitable chamber 70 in which the material is subjected to a calcining temperature. The chamber 70 may be made of any suitable material capable of withstanding the temperatures employed. For example, it may be made of fire clay, tile, or brick, or it may be made of a heat resisting metal. Chamber 70 is connected directly with a source of heat 50 which may be an auxiliary furnace, having a mixing or combustion chamber, into which a draft of diluting air or air to support combustion is supplied by means of blower 73. One furnace used by me had preheating passages in the furnace walls with adjustable openings so as to give thorough control of air inlets and give complete

combustion. A feeding mechanism 72 may discharge into said fan 73 to supply salts of alkali from metals, although such salts may also be introduced at any other point in the system, for example, at 68. In passing 70 through chamber 70 the hot gases calcine or either heat the disintegrated material and discharge into a third air separating chamber 53, from which the hot gases are discharged through pipe means 74 into the 75 above mentioned pipe means 64. The newly calcined, finely divided mineral contained in air separating chamber 53 is discharged through a feeding valve or mechanism 75 into pipe means which lead into pipe means 80 77, which in turn discharge into a fan or impeller 78 which discharges into a fourth air separating chamber 54 by means of pipe 79. Fan or impeller 78 may have a means of admitting cold air thereto as indicated at 81 85 so as to further cool the recently calcined material discharged from chamber 53. Chamber 54 discharges the finely divided calcined mineral through a feeding mechanism such as a tourniquet 84 into a storage bin 85 or other suitable receptacle 85, from which such material may be withdrawn through means 86 for bagging or other disposition. The gases leaving the air separating chamber 54 through pipe means 80, such gases 90 containing exceedingly minute particles of mineral matter, are led into a suitable dust collecting or air separating system, such as is indicated at 82, and which may be a stocking dust collector in which the minute particles are retained and collected in the bottom 95 of said collector in bin 83.

It is to be remembered that Figs. 1 and 2 are merely diagrammatic representations of the fundamental ideas embodied in my invention and that the angle at which the various pipe means connect the units may be varied to a large degree, and the number or location of fans or impellers may be changed with the conditions encountered in practice. 110 For example in Fig. 2, the calcining chamber 70 may be placed vertically and the calcined material discharged into a fireproof storage in which it is cooled before being passed through air separating chamber 53 or 115 54 or both. The addition of salts of alkali metals during or before the calcining operation is not necessarily followed in all cases, inasmuch as a purely calcining operation on finely divided mineral matter may be accomplished without such salts. Furthermore, the fans or impellers used in this invention may readily accomplish a certain amount of milling or disintegration, particularly when an easily reduced mineral, such as diatomaceous earth, is being treated. Whenever fans or impellers are therefore specified they may be understood to function not only as means of blowing but also as secondary disintegrators. The fundamental idea of novel- 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955

ty in my invention embraces the circulation of dust laden gases so as to remove such dust by contact with wet or moist material being treated, and the apparatus for such operation.

What is claimed is:

1. In a milling and drying process, the prevention of dust loss by disintegrating material containing moisture, passing such disintegrated material by pneumatic means into a separating apparatus, discharging the substantially dust-free air from such separating apparatus, discharging the disintegrated material from the separating apparatus into a heated gas, passing such gas and disintegrated material into a second separating apparatus and circulating the partly spent gas containing dust from the second separating apparatus to the moist disintegrated material.
2. In a combined milling and heating process, the prevention of dust loss by disintegrating material containing moisture, passing such disintegrated material by pneumatic means into a separating chamber, discharging the dust free gas from such chamber into the atmosphere, discharging the milled material from such chamber into a current of heated gas, conveying the milled material and gas to a second separating chamber and discharging the dust laden gas from such second chamber into the moisture-containing material so as to conserve such dust.
3. In a combined milling and heating process employing disintegrating apparatus, and primary and secondary air separating chambers, the circulation of partly spent heated gases containing dust from the secondary air separating chamber to the disintegrating apparatus so as to conserve such dust, and discharging dust free air from the primary air separating chamber.
4. In a combined milling and heating process, the prevention of dust loss by disintegrating diatomaceous earth containing moisture, passing such disintegrated diatomaceous earth by pneumatic means into a separating chamber, discharging the dust free gas from such chamber into the atmosphere, discharging the milled diatomaceous earth from such chamber into a current of heated gas, conveying the milled diatomaceous earth and gas to a second separating chamber and discharging the dust laden gas from such second chamber into the disintegrated moist diatomaceous earth so as to conserve such dust.
5. An apparatus for disintegrating and drying minerals without loss of dust comprising a substantially enclosed disintegrator, pneumatic means of conducting disintegrated mineral to an air separating chamber, gas discharge means from said chamber

and discharge means for disintegrated mineral from said chamber leading to a source of heated gas, means of conducting such heated gas and disintegrated mineral to a second separating chamber, and means for conducting the dust containing gases from such chamber into the disintegrator to conserve such dust.

6. An apparatus for disintegrating and drying diatomaceous earth containing moisture without loss of dust comprising a substantially enclosed disintegrator, pneumatic means of conducting moist disintegrated diatomaceous earth to an air separating chamber, gas discharge means from said chamber and discharge means for disintegrated diatomaceous earth from said chamber leading to a source of heated gas, means of conducting such heated gas and disintegrated diatomaceous earth to a second separating chamber, and means for conducting the dust containing gases from such chamber into the moist disintegrated material.

7. The herein described process of removing dust from dust laden air or gases produced in the milling and heating of moist siliceous material and the like; consisting in milling the siliceous material, heating the milled material, and returning the dry dust laden air or gases produced by such treatment into the moist material being treated previous to the drying thereof, whereby the dust is deposited on and retained by the wet or moist material.

8. The herein described process of milling and drying moist diatomaceous earth, consisting in first disintegrating the raw diatomaceous earth, discharging the disintegrated diatomaceous earth into a suitable heater; and returning the dust laden gases or air produced by such treatment into the moist diatomaceous earth being treated before the latter reaches the heater.

9. In a combined milling and heating process, the prevention of dust loss by disintegrating moisture-containing diatomaceous earth, passing such disintegrated diatomaceous earth by pneumatic means into a separating chamber, discharging substantially dust-free gas from such chamber into the atmosphere, discharging the milled diatomaceous earth from such chamber into a current of gas at a temperature above 300° F., conveying the milled diatomaceous earth and gas to a second separating chamber by pneumatic means, and discharging the dust containing gas from such second chamber into the initial disintegrator containing moisture-containing material so as to conserve such dust.

In testimony whereof I have hereunto subscribed my name this 25 day of June, 1925.

MCKINLEY STOCKTON,
